PORTABLE COMBINATION CASH AND
TICKET BOXAlbert U. Nelson and Charles E. Nelson,
Portland, Oreg.

Application March 17, 1948, Serial No. 15,444

4 Claims. (Cl. 312—146)

1

This invention pertains to combination ticket and cash boxes and relates particularly to a novel kit for use in the selling and collection of tickets.

It is a principal object of this invention to provide a combination of containers forming a portable kit which may be separated into a ticket sales unit and a ticket stub collector unit for use at their respective stations.

Another object of our invention is to provide a ticket sales unit and a ticket stub collector unit which may be combined to form a portable kit in which the stub collector unit encloses the sales unit in such manner as to prevent the spilling or intermixing of coins and currency retained in the latter.

Other objects and advantages of the present invention will appear from the following detailed description, taken in connection with the accompanying drawings, in which:

Fig. 1 is a perspective view of the assembled units comprising the present invention;

Fig. 2 is a sectional view taken along the lines 2—2 of Fig. 1 if the box were closed;

Fig. 3 is a perspective view of the ticket sales unit of the present invention with the currency tray raised to expose a currency storage compartment; and

Fig. 4 is a perspective view of the ticket sales tray with the ticket storage portion.

The ticket stub collector unit comprises a box 1 having a hinged lid 2 which forms a carrying case enclosing the containers comprising the sales and stub collector units of the present invention. The case is secured in closed position by means of locks 3 and is provided with a handle 4 for convenience in carrying. A compartment 5 is formed across the front side of the lid and extends the full length thereof. A slot 6 is cut in the side of the lid and communicates with the compartment. Thus, ticket stubs may be fed through the slot and collected in the compartment for counting at the end of a ticket taking period. A door 7 is slidably mounted in the inner wall of the compartment, as by the tongue-and-groove connection shown in Fig. 2 of the drawing, thereby providing an opening through which the stubs may be removed at the end of the ticket taking period.

The ticket sales unit comprises a series of trays mounted one upon the other and secured together at their rearward sides by means of hinges 8. The bottom tray is a ticket tray 9, and is provided with spindles 10 mounted upon the bottom of the tray to receive ticket rolls 11. The ends of the ticket rolls are threaded through slots 12 from

2

which the individual tickets may be readily detached as they are sold. Overlying the ticket tray is a second tray 13 across the front side of which coin compartments 14 are disposed. The bottoms of these compartments slope upwardly toward the front side to provide for easier extraction of coins herefrom. Immediately behind the coin compartments is a storage space 15 for additional tickets, cash, checks, etc. A currency tray 16 is hinged to the second tray and overlies the storage compartment 15, leaving the coin compartments exposed for use. Mounted upon the currency tray and extending forwardly thereon are spaced parallel slots 17 defining stalls for accommodating various denominations of currency.

The ticket sales unit is constructed and arranged to be removably received within the box 1 of the carrying case, as shown in Fig. 1 of the drawings. In this position, and when the lid 2 is folded downwardly to close the case, the inner walls of the stub compartment 5 closely overlie the coin compartments and the front edges of the currency stalls, while the top of the lid overlies the top edges of the currency stalls. In this manner, the assembled kit may be carried by the handle 4 without danger of spilling or intermixing the segregated currency, coins and tickets.

The kit is particularly adapted for use in connection with carnivals, fairs, games, etc., where no permanent booths are set up, and where space is at a premium. Two stations are generally required, namely, a booth where the tickets are sold, and a location for a doorman or gatekeeper who receives the tickets as the customers are admitted. The doorman retains the ticket stubs in order to check or otherwise determine the total attendance. These two units form the kit of the present invention.

In operation, the concessionaire places the rolls of tickets upon the spindle 10 in the ticket tray, arranges currency and coins in the various compartments provided therefor and deposits additional cash and tickets in the storage compartment. The sales unit is then placed in the box 1, the lid closed thereover, and the kit is ready to be transported to the place where tickets are to be sold. There the sales unit is removed from the box, the ends of the ticket rolls threaded through the slots 12, and the sales booth is ready for operation. The case is placed on end at the doorman's station, exposing the slot 6 through which the ticket stubs may be admitted to the stub collector compartment 5.

After the ticket sales have been terminated, the sales unit is replaced within the box 1, the lid is

closed, and the kit thereupon taken to the cashier responsible for checking the receipts. Upon opening the case the cashier opens the door 7, removes the ticket stubs, and checks their number against the number of tickets sold, as determined from the ticket rolls. The money deposited in the storage compartment and arranged in the currency and coin compartments is then readily counted and recorded to complete the accounting for the day. Coins, currency, tickets and additional supplies are then arranged in their various compartments, and the kit is re-assembled, ready for immediate use.

We claim:

1. In combination, a ticket sales unit and ticket stub collector unit; said ticket sales unit comprising, a ticket tray, a second tray hinged to and overlying said ticket tray, coin compartments in said second tray, a storage compartment behind said coin compartments, and a currency tray hinged to said second tray and overlying said storage compartment; said ticket stub collector unit comprising, a box having a hinged lid, a compartment therein; said ticket sales unit being constructed and arranged to be removably received in said box, the face of the lid and said compartment of the box being opposed to and complementary with and closely enclosing said currency and coin compartments when the lid is in closed position.
2. In combination, a ticket sales unit and a ticket stub collecting unit; said ticket sales unit comprising, a ticket tray, means on said tray rotatably securing ticket rolls therein, slots in the side of the tray for threading said rolls therethrough, a second tray hinged to and overlying said ticket tray, coin compartments in said second tray arranged across the front thereof, a storage compartment behind said coin compartments, a currency tray hinged to said second tray and overlying said storage compartment, and currency stalls on said currency tray; said ticket stub collector unit comprising, a box having a hinged lid, a compartment therein, said ticket sales unit being constructed and arranged to be removably received in said box, the face of the lid and said compartment of the box being opposed to and complementary with and closely enclosing said currency and coin compartments when the lid is in closed position.
3. A kit comprising, a ticket sales unit and a ticket stub collector unit; said ticket sales unit

comprising, a ticket tray, spindles on said tray rotatably securing ticket rolls therein, slots in the front side of the tray for threading said rolls therethrough, a second tray hinged to and overlying said ticket tray, coin compartments in said second tray extending the full depth thereof, a storage compartment behind said coin compartments, and a currency tray hinged to said second tray and overlying said storage compartment; said ticket stub collector unit comprising, a box having a hinged lid, a compartment therein, said ticket sales unit being constructed and arranged to be removably received in said box, the face of the lid and said compartment of the box being opposed to and complementary with and closely enclosing said currency and coin compartments when the lid is in closed position.

4. In combination, a ticket sales unit and a ticket stub collector unit; said ticket sales unit comprising, a ticket tray, spindles on said tray rotatably securing ticket rolls therein, slots in the front side of the tray for threading said rolls therethrough, a second tray hinged to and overlying said ticket tray, coin compartments in said second tray arranged across the front thereof and extending the full depth of said tray, a storage compartment behind said coin compartments, a currency tray hinged to said second tray and overlying said storage compartment, and spaced parallel slats defining currency stalls on said currency tray; said ticket stub collector unit comprising, a box having a hinged lid, a compartment therein, said ticket sales unit being constructed and arranged to be removably received in said box, the face of the lid and said compartment of the box being opposed to and complementary with and closely enclosing said currency and coin compartments when the lid is in closed position.

ALBERT U. NELSON.
